UNITED STATES PATENT OFFICE

1,998,672

CARD TABLE

Laurens Hammond, Chicago, Ill.

Application November 28, 1932, Serial No. 644,672

4 Claims. (Cl. 45—68.3)

My invention relates generally to tables and more particularly to card or bridge tables, and has for its object the provision of an improved table of this type equipped with a removable top 5 and having a readily replaceable top cover.

A further object of my invention is to provide an improved top for card tables in which the top cover is at all times resiliently tensioned to maintain the top playing surface of the table smooth 10 and free from wrinkles.

A further object of my invention is to provide an improved card table having a removable top and in which the top is resiliently held in place on the table.

15 Other objects will appear from the following description, reference being had to the accompanying drawing, in which

Fig. 1 is a perspective view of the table;

Fig. 2 is a bottom plan view of the top;

20 Fig. 3 is a fragmentary vertical sectional view taken on the line 3—3 of Fig. 2;

Fig. 4 is a vertical sectional view illustrating the means by which the top is secured to the sides of the table, and

25 Fig. 5 is a fragmentary bottom plan view of the top illustrating the means for securing the cover to the top.

The table comprises four side walls 10 which are supported by legs 12, preferably hinged at the 30 corners of the table and foldable so as to lie flush with the side walls. As best shown in Fig. 4, the side walls 10 are provided with a rabbet 14 at their upper edges to form a seat for the table top. The table top comprises a relatively rigid board 16

35 preferably made of a wood or a plastic composition. A plurality of shouldered rivets 18 are secured to the board 16 at spaced intervals adjacent the edges thereof and projecting from the bottom surface thereof. The top 16 has a flexible

40 cover 20 stretched thereover, a layer 22 of lightly packed felt or similar cushioning material being interposed between the cover 20 and the top 16. The edges of the cover 20 are folded around the edges of the board 16 and have hems 24 formed

45 thereon. The hems have portions thereof cut away to form openings 26 adjacent the rivets 18. A length of spring wire 28 extends through the full length of the hem 24 and has the portions thereof lying adjacent the opening 26 sprung outwardly and engaging beneath the heads of the rivets 18. The spring wires thus serve as means to pull the edges of the cover tightly over the edges of the board and to maintain the playing 50 surface of the table taut and free from wrinkles.

55 A plurality of brackets 30 are riveted to the

top board 16, one at each edge thereof, these brackets extending downwardly and each having a spring finger 32 riveted thereto. The spring finger has a V-shaped end portion engageable with a groove 34 formed in each of the side walls 10. The spring finger and its supporting bracket thus hold the top firmly in place. The bracket 30 has an inward extension 36 at its lower end by which the bracket and table top may be pushed upwardly when it is desired to remove the top from the table.

When it is desired to replace the top, it is necessary merely to "unbutton" the spring wires 28 from the headed rivets 18, whereupon the cover may be removed from the board 16. The spring wires 28 may then be withdrawn from the hems 24 and replaced in a new cover which can then be readily fastened to the top by pulling the spring wires over the headed rivets 18. The top may be replaced upon the table merely by dropping it into the rabbeted recesses 14 formed in the top edges of the sides, whereupon the spring fingers 32 will resiliently engage in the grooves 34 and hold the top in position.

While I have shown and described a particular embodiment of my invention, it will be apparent to those skilled in the art that various modifications in design and construction may be made without departing from the spirit of my invention. While I have illustrated my invention as incorporated in a card table, the invention may, as well, be used in other types of tables, for securing covers to ironing boards, and in similar articles.

What I claim as new and desire to secure by Letters Patent of the United States is:

1. A card table top comprising, a relatively rigid board having a plurality of studs spaced adjacent the peripheral edge of the board and projecting from the lower surface thereof, a flexible cover for said top having hems formed at its edges, said hems having a plurality of openings therein, and spring wires extending through said hems and sprung through said openings and around said studs thereby resiliently to stretch said cover over said top.

2. A card table top comprising, a board, a flexible cover for said top, said cover having its edges folded around the edges of said board, and a spring wire having alternate portions of the length thereof attached to said board and to said cover said spring wire being normally stressed and thus arranged to hold said cover stretched over said board by its resilient resistance to bending.

3. The combination of a relatively rigid board, a flexible cover extending over said board and

having its edges folded around the edge of said board, a spring wire bent to sinusoidal shape without exceeding the elastic limit of the wire and being alternately secured to said board and to 5 said cover respectively, whereby said cover is resiliently held taut over said board.

4. In a work supporting covering, the combination of a substantially plane rigid work supporting member having a plurality of downwardly extending cover securing studs located on its lower side adjacent the periphery thereof, said studs having retaining shoulders, and a flexible covering for said member comprising a piece of flexi-

ble material of sufficient size and similar shape to said member, said covering extending over the edges of said member and under the lower surface to a point adjacent said studs, said covering being provided with a plurality of spaced points of attachment about its periphery for resilient metal wire means, and said wire means being bowed away from the edge of said covering between said spaced points of support and hooked over said studs whereby said resilient metal wire 10 stretches said covering on said member. 5

LAURENS HAMMOND.
